Claims priority, application Canada Mar. 3, 1962

Term of patent 14 years

(Cl. D58—13)

The figure is a top perspective view of a compartmented packaging tray, showing my new design.

The characteristic feature of my design resides in the continuously, vertically corrugated margin, vertically scalloped at the ends of the recessed, transverse compartments which are divided by spaced, segmental partitions, as shown.

I claim:

The ornamental design for a compartmented packaging tray, as shown and described.
